UNITED STATES PATENT OFFICE.

WILLIAM C. BOECK, OF HARTFORD, WISCONSIN, ASSIGNOR TO GEORGE SOTDORUS, OF GLEN ROCK, PENNSYLVANIA.

CONDIMENT-SHAKER.

1,123,228.

Specification of Letters Patent.

Patented Jan. 5, 1915.

Application filed May 13, 1912. Serial No. 696,878.

To all whom it may concern:

Be it known that I, WILLIAM C. BOECK, a citizen of the United States, and resident of Hartford, in the county of Washington and State of Wisconsin, have invented certain new and useful Improvements in Condiment-Shakers; and I do hereby declare that the following is a full, clear, and exact description thereof.

10 The object of my invention is to provide a simple, economical and durable shaker for condiments, the construction and arrangement being such that a vessel having compartments formed by a longitudinal partition is provided for the reception of different ingredients as for example salt or pepper, the said vessel being also provided with a perforated cover-cap having a perforated spring-controlled shutter for each cap which 15 is adapted to be independently manually manipulated whereby the perforations in the cap and shutter are brought into register for the discharge of the selected condiment. It is also contemplated to provide a 20 detachable bottom cap for the vessel whereby the same may be filled without removing the discharge or mouth cap.

With the above objects in view the invention consists in certain peculiarities of construction and combination of parts as set 25 forth hereinafter with reference to the accompanying drawings and subsequently claimed.

In the drawings Figure 1 represents a 30 longitudinal sectional view of a shaker embodying the features of my invention; Fig. 2, a top plan view of the same with parts broken away and parts in section to more clearly show structural features, and Fig. 3, a side elevation of the vessel mouth and cap illustrating one means of securing said cap to the mouth.

Referring by characters to the drawings, 35 Fig. 1 represents a vessel having an open discharge mouth 1' and an open bottom 1'' which constitutes a filling mouth. The filling mouth is provided with a detachable cap closure 2, which closure as shown is in screw threaded engagement with the bottom 40 of the vessel, it being understood however that in some instances other well known means may be employed for securing the cap closure to the vessel. The vessel is also provided with a longitudinally arranged partition 3 whereby said vessel is divided in com-

partments or chambers for the reception of different ingredients. The vessel adjacent to the discharge mouth is provided with a pair of radially extending studs 4 which serve as keepers for a perforated mouth-cap 5, the same being in the form of a slip cover and is provided with a depending flange that is formed with L-shaped slots 6 for locking engagement with the studs whereby the mouth-cap is detachably secured thereto. It is apparent however that I may, in some instances, without departing from the spirit of my invention, secure the mouth-cap by a screw-threaded connection with the vessel in the same manner as that shown in connection with the bottom cap, or the stud and slot securing means just mentioned may be utilized for said bottom cap.

The mouth-cap as shown rests flatly upon the upper edge of the vessel mouth and partition whereby the two compartments are sealed and secured by rivets 7, 7, to the perforated face of the mouth-cap 5 are slidable perforated shutters 8, 8, upon opposite sides of the partition. Each shutter is provided with a slot 8' for engagement with the shank of the rivet whereby said shutters are capable of having slight sliding movement relative to the cap to permit registration of the shutter and cap apertures. Each shutter is also provided with a depending lug 9 that carries a push-pin 10, each of which push-pins extends through apertures in the wall of the vessel whereby the shutters may be manually operated. The push-pins 10 so arranged not only serve as means for actuating the shutters, but after the slip-cover or mouth-cap 5 carrying the shutters is adjusted to the mouth of the vessel, the pins 10 being fitted through the vessel apertures and in engagement with the lugs 9, also firmly hold the cover or cap in place. Thus said cover cannot be removed or become loose by twisting upon the pins 4 due to this locking result of the pins in addition to their function of forming means for actuating the shutters. The shutter perforations are normally held staggered with relation to the cap perforations by coiled springs 11, each of which coiled springs is interposed between the partition wall and an ear 12 that depends from the shutter, the ear and partition wall at this point being each provided with nibs for the support of the ends of the coiled spring. As shown in the plan view

the shutters are semicircular in form and are adapted to move inwardly toward the partition when it is desired to bring their perforations in registration with the cap 5 perforations, it being apparent from the foregoing description that when a selected condiment is desired to be used the operator presses the button that projects through the vessel wall of that particular condiment 10 compartment whereby the shutter apertures are brought into register with the cap apertures and the contents of this particular chamber can thus be shaken out or discharged. It should also be understood that 15 the walls of the vessel may be marked to indicate the ingredient contained in the respective compartments, the marking being adjacent to the push buttons.

While I have shown and described the 20 bottom of the vessel as being open for filling purposes, I may, without departing from the spirit of my invention, form said bottom with a permanent closure and remove the cap for filling purposes in which instance it would only be necessary to disconnect the push pins and after the cap has 25 been seated replace the same.

In some instances it may be desirable to place the springs 11 outside of the vessel to

prevent corrosion thereof, in which case 30 the springs 11 and ears 12 could be dispensed with and the coiled springs interposed about the push-button rods 10 whereby the same mechanical action would be produced with relation to the shutter.

I claim:

A shaker comprising a longitudinally partitioned vessel having an open mouth provided with apertures adjacent thereto, and a slip cover perforated cap for the 40 mouth; spring-controlled perforated shutters in slideable union with the cap, a lug depending from each shutter, a push-pin extending through each vessel aperture and engageable with a companion shutter-lug 45 whereby said shutters are actuated and the perforated cap is maintained in its adjusted position with relation to the mouth of the vessel.

In testimony that I claim the foregoing 50 I have hereunto set my hand at Hartford in the county of Washington and State of Wisconsin in the presence of two witnesses.

WILLIAM C. BOECK.
